CLOTH SPREADING MACHINE

Raymond E. Sayles, Kansas City, Mo.

Application October 27, 1947, Serial No. 782,286

13 Claims. (Cl. 270—31)

1

This invention has to do with a machine for feeding cloth or like flexible material from a roll or bolt thereof and spreading the same in long sheets relatively superimposed preparatory to subsequent use in the making of wearing apparel and other articles, the primary object being to provide such machine that is reciprocable over the surface upon which the cloth is to be spread and adaptable to spread the cloth as the machine reciprocates in either direction and further capable of spreading the cloth with all sheets thereof facing in the same direction or with the faces thereof alternately disposed as desired.

The most important object of this invention is the provision of a cloth spreading machine having a reciprocable carriage provided with a rotatable cloth supporting frame to the end that the frame may be shifted at each end of the path of travel of the carriage whereby cloth may be spread in either direction of travel of the carriage, and further whereby a predetermined face of the cloth may be disposed upwardly irrespective of the direction of travel of the carriage and frame thereon.

Another important object of this invention is the provision of a cloth spreading machine having a wheeled carriage, one of the wheels thereof providing the power for rotating a roll of cloth to be spread through the medium not only of a rotatable element frictionally engaging the roll of cloth, but through a rotatable member frictionally receiving the cloth as the same unwinds from the roll.

Another object of this invention is the provision of a cloth spreading machine of the aforementioned character having an assembly of parts rendering the feeding mechanism for the roll of cloth operable to rotate the roll of cloth in a given direction irrespective of the relative position of the rotatable frame upon the carriage, and also operable in the same manner with the frame in either of two positions relative to the carriage.

A further object of this invention is to provide a cloth spreading machine having a swingable apron on the rotatable frame for receiving the cloth being fed from the roll thereof and disposed in overlying relationship to the carriage, said machine having structure operable automatically to swing the apron to a position clearing the carriage as the frame is rotated to and from the two positions above mentioned with respect to the reciprocable carriage.

A still further object of this invention is the provision of a cloth spreading machine having

2

manually manipulable structure operably associated with the aforesaid automatic apron swinging means for swinging the apron to and from a number of selected positions and capable of so swinging the apron independently of the rotation of the frame upon the carriage.

Other objects of this invention include the manner in which a train of gears, shafts, sprocket wheels and interconnecting chains are arranged between one of the rotatable wheels of the carriage and the cloth feeding means to permit rotation of the roll of cloth in one direction irrespective of the direction of rotation of the wheel, there being manually controllable elements for reversing the direction of travel of certain of said gears as the direction of travel of the reciprocable carriage is reversed; the way in which such mechanism is rendered operable to rotate the roll of cloth in one direction irrespective of the relative positions of the frame and the carriage; and numerous other details of construction and arrangement of parts, all of which will be made clear or become apparent during the course of the following specification taken with the accompanying drawings, wherein:

Fig. 1 is an end elevational view of a cloth spreading machine made in accordance with my present invention.

Fig. 2 is a fragmentary end elevational view 30 thereof opposite to that shown in Fig. 1.

Fig. 3 is a rear elevational view thereof, parts being broken away to reveal details of construction.

Fig. 4 is a fragmentary cross sectional view 35 taken on line IV—IV of Fig. 3.

Fig. 5 is a fragmentary cross sectional view taken on line V—V of Fig. 3, looking in the direction of the arrows; and

Fig. 6 is a fragmentary cross sectional view 40 taken on line VI—VI of Fig. 5 and looking in the direction of the arrows.

Previous attempts have been made to produce machines capable of spreading cloth in superimposed layers over a flat surface as the same is 45 removed from a roll thereof, but heretofore such machines have been unsatisfactory for the reason that they were incapable of spreading the cloth during both directions of reciprocation of the machine or were incapable of, at the same time, disposing the same side of each sheet of cloth in the same direction. These objections and many others have been overcome in the machine about to be described which, as shown in the drawings, includes a reciprocable carriage 50 broadly designated by the numeral 10.

This carriage 10 includes a pair of spaced apart substantially triangular-shaped plates 12 joined together at their uppermost end by an elongated channel-shaped frame member 14.

A pair of spaced apart rods 16 spaced below this frame member 14 also span the distance between the plates 12 and interconnect the plates 12. One of these plates 12 is provided with a pair of spaced apart wheels 18 rotatably mounted thereon and movable along a flat surface 20 over which the carriage 10 reciprocates and upon which surface 20 the cloth is to be spread as hereinafter more fully set forth.

The other plate 12 has rotatably mounted thereon a pair of pulley wheels 21 movable along and guided by an elongated L-shaped track 22, mounted in any suitable manner upon the surface 20.

A frame broadly designated by the numeral 24 and disposed above the carriage 10 is rotatably supported by the frame member 14 of carriage 12. This frame 24 includes a pair of spaced apart up-standing arms 26 each mounted at their lowermost ends upon an elongated channel member 28. A V-shaped notch 32 is cut into each of the arms 24 at their uppermost ends and a pair of rollers 34 mounted thereon adjacent the apex of each notch 32 rotatably receive the ends of a spindle 36 for a roll of cloth 38. In other words, this roll of cloth 38 to be spread, is disposed between the arms 24 and has its spindle 36 loosely resting upon the rollers 34 adjacent the notches 32. Means for rotatably mounting the frame 24 and all parts carried thereby on a normally substantially vertical axis, is clearly illustrated in Figs. 5 and 6 of the drawings.

A vertically disposed cylinder 40 is secured in depending relationship to a plate 42 which in turn is welded or otherwise attached to the member 28 of frame 24 and within the channel defined thereby. This cylinder 40 is telescoped over an upstanding supporting member 43 secured to the uppermost face of the frame member 14 of the carriage 10 intermediate the ends thereof. This member 43 is circular in cross section and has an outside diameter slightly less than the inside diameter of the cylinder 40 to the end that the latter is freely rotatable thereon.

A laterally and upwardly extending flange 44 integral with the member 43 near the lowermost end thereof provides a surface for receiving the normally lowermost end of the cylinder 40. One of the wheels 18 of the carriage 10 has secured thereto and rotatable therewith, a sprocket wheel 46 for receiving an endless chain 48 that also passes around a sprocket 50. This sprocket 50 is mounted upon one end of a shaft 52 which passes through one of the plates 12 of carriage 10 and terminates at its opposite end near the supporting means 42 for the frame 24. This innermost end of the shaft 52 is rotatably mounted in a bearing 54 depending from the frame member 14 of the carriage 10.

Shaft 52 has slidably mounted thereon near the bearing 54, a sleeve 56 that is held for rotation with the shaft 52 by a pin 58 mounted in shaft 52 and extending laterally therefrom. This pin 58 passes through an elongated slot 60 formed in the sleeve 56.

A pair of pinions 62 and 64 are secured directly to each end respectively of the sleeve 56 and these pinions 62, 64 are also each slidably on the shaft 52 with the sleeve 56. Reciprocation of the pinions 62 and 64 on the shaft 52 is accomplished manually through the medium of a U-shaped

bracket 66 having the legs thereof slidably mounted upon the shaft 52 through the medium of openings 68 therein, said pinions 62 and 64 and sleeve 56 being disposed between the two legs of bracket 66.

A rod 70 having one end thereof pivotally mounted upon the bracket 66 as at 72, extends in substantially parallelism with the frame member 14 through one of the plates 12 having pulley wheels 21 mounted thereon. This rod 70 is slideable within an opening formed in said plate 12 and has its end turned laterally to form a handle 74. It is clear that as handle 74 is grasped by the operator, the rod 70 may be reciprocated and thereby cause the pinions 62 and 64 to slide upon the shaft 52. The end of the shaft 52 adjacent the bearing 54 directly underlies a bevel gear 76 mounted upon one end of a vertical shaft 78 passing through an opening 80 formed in the supporting member 43. The distance between the pinions 62 and 64 is greater than the diameter of the bevel gear 76 to the end that pinions 62 and 64 may be disposed in a neutral position as illustrated in Fig. 3. As the rod 70 is moved inwardly, the pinion 64 will be brought into meshing relationship with the gear 76 to rotate the latter in one direction as the shaft 52 rotates in a given direction and when the rod 70 is moved outwardly, the pinion 62 will be brought into operative engagement with the gear 76 to rotate the latter in an opposite direction when shaft 52 rotates in said given direction. The vertical shaft 78 also has a second bevel gear 82 mounted upon its uppermost end within the cylinder 40.

It is notable at this juncture that the member 43 terminates in spaced relation from the uppermost end of the cylinder 40 to provide clearance for this gear 82 and for a pair of gears 84 and 86 enmeshed with gear 82 in relative opposed relationship. The gear 86 is mounted upon the innermost end of a stub shaft 88 that rotatably passes through the cylinder 40 and has affixed to its outermost end a sprocket wheel 90. An elongated shaft 92 rotatably mounted within the frame member 28 has a sprocket wheel 94 secured thereto intermediate its ends and an endless chain 96 operably interconnects the sprocket wheels 90 and 94.

One end of the shaft 92 extends outwardly through an end wall of the member 28 and has a sprocket 98 secured thereto.

A pair of upstanding arms 100 are swingably mounted at one end thereof to opposite ends respectively of the shaft 92 and are joined by a tie rod 102. These arms 100 are disposed to one side of the arms 26 of frame 24 and are interconnected at their uppermost ends by a rotatable shaft 102 that is driven by an endless chain 104 passing over the sprocket 98 and a sprocket 106 secured to one end of the shaft 102.

A roller 108 substantially coextensive in length with the shaft 102 is disposed between the arms 100 and secured to the shaft 102 for rotation therewith. This roller 108 is covered with a suitable roughened material 110 for frictionally engaging the roll 38 and the roller 108 is yieldably held tightly against the roll of cloth 38 by a spring 112 interconnecting at least one of the arms 100 with the proximal arm 26 of frame 24.

Referring again to Fig. 6 of the drawings, the gear 84 within the cylinder 40 is mounted upon one end of a shaft 114. This shaft 114 rotatably passes through the cylinder 40 in diametrically opposed relationship to the stub shaft 88 and terminates at its opposite end near the outer-

most face of one of the arms 26 next adjacent to the arm 100 having chain 104 disposed therealong.

This shaft 114 rotatably passes through an opening within this arm 26 and has secured to its outermost end a sprocket wheel 116. The frame member 28 carries a laterally extending substantially horizontal arm 118 that projects oppositely to the shaft 92.

A roller 120 also wrapped with frictionable material (not shown) as at 110 with respect to the roller 108, spans the distance between these two arms 118 near their outermost ends. A shaft 122 for this roller 120 rotatably mounted within the arms 118 carries a sprocket wheel 124 at one end thereof. The sprockets 116 and 124 are interconnected by an endless chain 126 that also passes over an idler sprocket 128. A roller 129, rotatably mounted between the arms 118 inwardly from the elongated roller 120, has an out-turned flange 130 at each end thereof.

As shown in Fig. 5, a pair of spaced apart L-shaped brackets 131 mounted upon the member 28 adjacent the arms 118 rotatably carry a shaft 132 extending between the arms 118 substantially parallel to the rollers 120 and 130 and 25 slightly therebelow.

An apron broadly designated by the numeral 134 comprises a pair of spaced apart arms 135, each secured at one end thereof directly to the shaft 132 and having a pair of rollers 136 and 137 interconnecting their opposite ends. These rollers 136 and 137 are spaced apart and substantially parallel and are also parallel with the shaft 132. This apron 134 normally overlies the carriage 10 and extends at an angle downwardly and forwardly from the arms 118 that mount rollers 120 and 130.

It is thus seen that the apron 134 is swingable on a horizontal axis with the shaft 132 and means for holding apron 134 in a given position includes a link 138. This link 138 is pivotally mounted intermediate its ends as at 140 upon a bracket 142 depending from the plate 42. An arm 144 rigidly secured to the shaft 132 is connected to the link 138 by a short link 146. This link 146 is pivotally connected at the ends thereof with the dog 144 and the link 138 respectively. The link 138 carries at the end thereof opposite to the link 146, a roller 148 disposed to ride along the uppermost edge 150 of the flange 44. In other words, this flange 44 extends upwardly from the member 14 in circumscribing relationship to the lowermost end of the cylinder 40.

A pair of diametrically opposed notches 152 are formed in the uppermost edge 150 of the flange 44 in the path of travel of the roller 148. It is thus seen that as the frame 24 is rotated upon the carriage 10 to either of two positions where the roll of cloth 38 is substantially parallel to the longitudinal axis of the carriage 10, the roller 148 will be disposed in one of the two diametrically opposed notches 152, but as the frame 24 is rotated, this roller 148 will move to the edge 150 of flange 44 and thereby cause the apron 134 to swing upwardly to a point where the same will clear the carriage 10 as the frame 24 is thus rotated.

The height of the lowermost edge of the apron 134 with respect to the surface 20 may be adjusted manually through mechanism engageable with the arm 138. This mechanism includes a short vertically disposed reciprocable bar 154 slidably mounted on a bracket 156 depending from member 28 and rotatably receiving a rod 160. This rod 160 extends through one end of

the member 28 and has secured thereto near one end thereof a disc-like cam member 162. This member 162 is eccentrically secured to the rod 160 and overlies the uppermost end of the bar 154. The opposite end of the rod 160 has a cog wheel 164 secured thereto and a handle 166 disposed outwardly from the cog wheel 164 permits manual rotation of the rod 160.

A swingable dog 168 is yieldably held in a 10 position engageable with the cog wheel 164 by a spring 170. Rotation of the rod 160 and the cam member 162 thereon will move the bar 154 downwardly and thus actuate the arm 138 on pivot point 140 to raise the apron 134 to desired positions.

The dog 168 serves to hold the apron 134 in 15 such selected position. This manually operable mechanism just described obviously has no effect upon the automatic means for raising apron 134 just previously described since the arm 138 is free to swing independently of the bar 154 and cam 162.

A pair of shoes 172 depending from each end of the member 28 respectively, ride across a vertically reciprocable pin 174 as the frame 24 is rotated upon the carriage 10. This pin 174 is slidably mounted within the member 14 and a spring 176 coiled thereabout, yieldably holds the same at the uppermost end of its path of travel.

A T-shaped handle 178 having one end thereof extending through a plate 12 of carriage 10, has an extension 180 secured to one leg of the handle 178 near its innermost end, this extension 180 being slotted at its free end for slidably receiving the pin 174. As the handle 178 is rotated in one direction, the extension 180 moves against a collar 182 on the pin 174 pulling the same downwardly against the action of the spring 176 and removing said pin 174 from within an opening 184 formed in the respective shoe 172 so disposed above pin 174.

As shown in Fig. 3, the manually manipulable rod 70 is provided with three cavities 186 for receiving the lowermost pointed end of a spring 45 loaded pin 188 mounted within one of the plates 12. Through the use of this pin 188, the rod 70 is held in either of the two operative positions of pinions 62 and 64 or in the neutral position.

In operation, the roll of cloth 38 is placed upon 50 the arms 24 and the cloth itself threaded downwardly below the rollers 130 between rollers 120 and 130 and over the top of the roller 120. This cloth then extends downwardly to the apron 134 and toward the rollers 136 and 137 thereof. As 55 clearly indicated in Fig. 1, the cloth extends over the roller 137 between rollers 136 and 137 and under the roller 136. As the carriage 10 is reciprocated to the right when viewing Fig. 1, the roll 38 will be rotated in a direction to unwind the 60 cloth thereof and the roller 120 will be rotated to exert a pulling action on said cloth in the following manner:

Rotation of the one wheel 18 having sprocket 46 thereon will cause rotation of the shaft 52 in 65 the direction of the arrow shown in Fig. 3 of the drawing, which will be the same direction of rotation as that of wheel 18. When pinion 62 is moved into meshing relationship with the gear 76 to rotate the gear 82, the shaft 114 will be 70 caused to rotate in the opposite direction as that of the sprocket 46, thereby causing roller 120 to rotate by medium of the chain 126 in a direction to exert a pulling action upon the cloth from the roll 38 thereof. Simultaneously, when the pinion 75 62 is in operative engagement with gear 76, the

gear 86 will rotate in a direction to cause rotation of the sprockets 90 and 94, and consequently, the shaft 92 in the same direction as the rotation of sprocket 46. This will cause the roller 108 to rotate in the direction of the arrow shown in Fig. 1, thereby actuating the roll 38 in a cloth feeding direction.

If desired, when the carriage 10 has been moved to the opposite end of the surface 20, the cloth may either be cut or folded upon itself and the next layer of cloth spread thereon as the carriage 10 is reciprocated back to the point of beginning. When the carriage 10 is thus returned to its point of beginning, obviously, the wheel 18 having sprocket 46 thereon will rotate in a direction opposite to that just above described and therefore, the rod 70 must be actuated to move the pinion 62 out of engagement with the gear 76 and to place pinion 64 into meshing relationship with the gear 76. Such reversal of the parts will cause the roller 122 to rotate in the same direction as the sprocket 46 and the roller 108 to rotate in a direction opposite to that of sprocket 46.

It is notable that the roller 108 always travels in the same direction as indicated by the arrow in Fig. 1. It is further to be noted that the roller 120 always rotates in a direction opposite to the direction of rotation 108 irrespective of the direction of travel of carriage 10 and regardless of the position of the frame 24 upon the carriage 10.

When the machine is operated as just above described, the layers of cloth on the surface 20 will have their outermost faces alternately disposed. This may be objectionable in many cases when such layers of cloth are subsequently worked with and therefore, to the end that each layer may have the same face thereof disposed upwardly, the frame 24 is rotated to an opposite position with respect to carriage 10 at each end of the path of travel of carriage 10. When the machine is operated in this manner, the cloth must be cut at the end of each spreading operation and by releasing the pin 174, the frame 24 and all parts thereon, may be rotated upon carriage 10. When this is done, the roller 148 on arm 138 will move from one of the notches 152 and ride along the edge 150 to raise the apron 134 to a position clearing the carriage 10. When the frame 24 has been completely turned to a position where the opposite shoe 172 engages the pin 174, the roller 148 will move into the opposite notch 152, thereby returning the apron 134 to the original operative position as governed by the position of bar 154. After such rotation of the frame 24 has taken place, the pinions 62 and 64 are reversed in the same manner as above described and another layer of cloth is spread with the same face disposed upwardly as was true in the layer of the cloth next below. As the stack of spread cloth increases in height upon the surface 20, the apron 134 is progressively raised by actuating the handle 166. A grip 190 on one of the plates 12 of the carriage 10 having the handle 178 therein, permits easy manual reciprocation of the carriage 10 along guiding track 22.

One of the most important features of this invention as will readily become apparent to those skilled in the art, lies in the fact that as the machine is placed in operation and as the frame 24 is rotated upon the carriage 10 at each end of the path of travel of the latter, no rethreading of the cloth whatsoever is necessary within the plurality of rollers 130, 120, 137 and 138. In other words, when rotation of the frame 24 takes place, the entire assembly disposed above the

carriage 10 and rotatable thereon, is moved as a unit. It is also notable that this cloth spreading machine differs from conventional devices of this character in that there is no need for cloth catching clamps or weights. In other words, as the carriage reciprocates, there is no tendency whatsoever to pull the length of cloth upon the surface 20 along with carriage 10, thereby eliminating the necessity of having means for holding such spread cloth in place as the machine reciprocates.

This feature is made possible by the exertion of driving force upon the roll of cloth 38 through the medium of the roller 108.

Having thus described the invention, what is claimed as new and desired to be secured by Letters Patent is:

1. A cloth spreading machine of the kind set forth comprising a reciprocable wheeled carriage; a frame on the carriage having means for rotatably supporting a roll of cloth to be spread; structure operably connected to at least one of the wheels of said carriage for rotating said roll of cloth as said one wheel rotates during movement of the carriage; and manually controllable mechanism for rendering said structure operable to rotate the roll of cloth in one predetermined direction irrespective of the direction of travel of said carriage, said structure including a rotatable member having means for yieldably holding the same in frictional engagement with the roll of cloth.

2. A cloth spreading machine of the kind set forth comprising a reciprocable wheeled carriage; a frame on the carriage having means for rotatably supporting a roll of cloth to be spread; structure operably connected to at least one of the wheels of said carriage for rotating said roll of cloth as said one wheel rotates during movement of the carriage; and manually controllable mechanism for rendering said structure operable to rotate the roll of cloth in one predetermined direction irrespective of the direction of travel of said carriage, said structure including a rotatable member having means for yieldably holding the same in frictional engagement with the roll of cloth, a driven shaft and a drive shaft operably joined to the member and said one wheel respectively, and a train of gears interconnecting 50 said shafts.

3. A cloth spreading machine of the kind set forth comprising a reciprocable wheeled carriage; a frame on the carriage having means for rotatably supporting a roll of cloth to be spread; structure operably connected to at least one of the wheels of said carriage for rotating said roll of cloth as said one wheel rotates during movement of the carriage; and manually controllable mechanism for rendering said structure operable to rotate the roll of cloth in one predetermined direction irrespective of the direction of travel of said carriage, said structure including a rotatable member having means for yieldably holding the same in frictional engagement with the roll of cloth, a driven shaft and a drive shaft operably joined to the member and said one wheel respectively, and a train of gears interconnecting said shafts, said mechanism including a pair of drive gears forming a part of said train of gears and shiftable alternately to and from a position operably interconnecting said shafts.

4. A cloth spreading machine of the character described comprising a reciprocable carriage; a frame rotatably mounted on said carriage and having means thereon for supporting a roll of

cloth to be spread; structure having parts on the carriage and on the frame respectively for feeding the cloth from said roll thereof as the carriage reciprocates; and manually controllable mechanism for rendering said structure operable to feed said cloth from one predetermined side of the frame when said frame is rotated to either of two positions relative to said carriage.

5. A cloth spreading machine of the character described comprising a reciprocable carriage; a frame rotatably mounted on said carriage and having means thereon for supporting a roll of cloth to be spread; structure having parts on the carriage and on the frame respectively for feeding the cloth from said roll thereof as the carriage reciprocates; manually controllable mechanism for rendering said structure operable to feed said cloth from one predetermined side of the frame when said frame is rotated to either of two positions relative to said carriage; and an apron mounted on said one side of the frame for receiving the cloth being fed from the roll.

6. A cloth spreading machine of the character described comprising a reciprocable carriage; a frame rotatably mounted on said carriage and having means thereon for supporting a roll of cloth to be spread; structure having parts on the carriage and on the frame respectively for feeding the cloth from said roll thereof as the carriage reciprocates; manually controllable mechanism for rendering said structure operable to feed said cloth from one predetermined side of the frame when said frame is rotated to either of two positions relative to said carriage; and an apron mounted on the said one side of the frame for swinging movement to and from a position overlying said carriage, said apron receiving the cloth being fed from said roll.

7. A cloth spreading machine of the character described comprising a reciprocable carriage; a frame rotatably mounted on said carriage and having means thereon for supporting a roll of cloth to be spread; structure having parts on the carriage and one the frame respectively for feeding the cloth from said roll thereof as the carriage reciprocates; manually controllable mechanism for rendering said structure operable to feed said cloth from one predetermined side of the frame when said frame is rotated to either of two positions relative to said carriage; an 50 apron mounted on the said one side of the frame for swinging movement to and from a position overlying said carriage, said apron receiving the cloth being fed from said roll; and apparatus having parts on the frame and carriage respectively for automatically swinging said apron to and from a position clearing said carriage as the frame is rotated on the carriage.

8. A cloth spreading machine of the character described comprising a reciprocable carriage; a frame rotatably mounted on said carriage and having means thereon for supporting a roll of cloth to be spread; structure having parts on the carriage and one the frame respectively for feeding the cloth from said roll thereof as the carriage reciprocates; manually controllable mechanism for rendering said structure operable to feed said cloth from one predetermined side of the frame when said frame is rotated to either of two positions relative to said carriage; an apron mounted on the said one side of the frame for swinging movement to and from a position overlying said carriage, said apron receiving the cloth being fed from said roll; apparatus having parts on the frame and carriage respectively for 75

automatically swinging said apron to and from a position clearing said carriage as the frame is rotated on the carriage; and manually manipulable means on said frame engageable with the parts of said apparatus on the frame for swinging said apron independently of rotation of the frame.

9. A cloth spreading machine of the character described comprising a reciprocable carriage; a frame rotatably mounted on said carriage and having means thereon for supporting a roll of cloth to be spread; structure having parts on the carriage and on the frame respectively for feeding the cloth from said roll thereof as the carriage reciprocates; manually controllable mechanism for rendering said structure operable to feed said cloth from one predetermined side of the frame when said frame is rotated to either of two positions relative to said carriage; an apron mounted on the said one side of the frame for swinging movement to and from a position overlying said carriage, said apron receiving the cloth being fed from said roll; apparatus having parts on the frame and carriage respectively for automatically swinging said apron to and from a position clearing said carriage as the frame is rotated on the carriage; manually manipulable means on said frame engageable with the parts of said apparatus on the frame for swinging said apron independently of rotation of the frame; and elements forming a part of said last mentioned means for releasably holding said apron in a number of selected positions along its path of travel.

35. 10. In a cloth spreading machine of the character described, a carriage; a frame rotatably mounted on said carriage and having means for supporting a quantity of the cloth to be spread; an apron swingably mounted on said frame in overlying relation to said carriage for receiving the cloth from said frame; and apparatus having parts on the frame and carriage respectively for automatically swinging said apron to and from a position clearing said carriage as the frame is rotated on the carriage.

40. 11. In a cloth spreading machine of the character described, a carriage; a frame rotatably mounted on said carriage and having means for supporting a quantity of the cloth to be spread; an apron swingably mounted on said frame in overlying relation to said carriage for receiving the cloth from said frame; and apparatus having parts on the frame and carriage respectively for automatically swinging said apron to and from a position clearing said carriage as the frame is rotated on the carriage, said apparatus including a swingable link on said frame having one end thereof operably connected to said apron, and means on the carriage engageable with the opposite end of the arm for swinging the latter as the frame rotates.

45. 12. In a cloth spreading machine of the character described, a carriage; a frame rotatably mounted on said carriage and having means for supporting a quantity of the cloth to be spread; an apron swingably mounted on said frame in overlying relation to said carriage for receiving the cloth from said frame; apparatus having parts on the frame and carriage respectively for automatically swinging said apron to and from a position clearing said carriage as the frame is rotated on the carriage, said apparatus including a swingable link on said frame having one end thereof operably connected to said apron, and means on the carriage engageable with the op-

posite end of the arm for swinging the latter as the frame rotates; and manually manipulable means on said frame engageable with said link near said one end thereof for swinging said apron independently of rotation of the frame.

13. In a cloth spreading machine of the character described, a carriage; a frame rotatably mounted on said carriage and having means for supporting a quantity of the cloth to be spread; an apron swingably mounted on said frame in overlying relation to said carriage for receiving the cloth from said frame; apparatus having parts on the frame and carriage respectively for automatically swinging said apron to and from a position clearing said carriage as the frame is rotated on the carriage, said apparatus including a swingable link on said frame having one end thereof operably connected to said apron, and means on the carriage engageable with the opposite end of the arm for swinging the latter as the

frame rotates; and manually manipulable means on said frame engageable with said link near said one end thereof for swinging said apron independently of rotation of the frame, said last mentioned means including a cam-actuated, slidable bar having one end thereof bearing against said link, and elements for holding the said cam in a number of selected positions whereby said apron is rendered adjustable along its path of swinging movement.
